LOUVER GRID FOR LIGHTING FIXTURE

Maurice Eisenberg, Chicago, Ill., assignor to Solar Light Manufacturing Co., Melrose Park, Ill., a corporation of Illinois

Filed Oct. 12, 1966, Ser. No. 4,248

Term of patent 14 years

(Cl. D48—23)

FIGURE 1 is a top plan view of a louver grid for lighting fixture, showing my new design;

FIGURE 2 is a bottom plan view thereof;

FIGURE 3 is a side elevational view thereof; and

FIGURE 4 is an end elevational view thereof.

I claim:

The ornamental design for a louver grid for lighting fixture, as shown.
